W. F. DECKER,
APPARATUS FOR DRYING BRICKS.
APPLICATION FILED SEPT. 29, 1906.

Patented June 1, 1909.

3 SHEETS—SHEET 3.

UNITED STATES PATENT OFFICE.

WILLIAM F. DECKER, OF GOSHEN, NEW YORK.

APPARATUS FOR DRYING BRICKS.

No. 923,340.

Specification of Letters Patent.

Patented June 1, 1909.

Application filed September 29, 1906. Serial No. 336,782.

To all whom it may concern:

Be it known that I, WILLIAM F. DECKER, a citizen of the United States, residing at Goshen, in the county of Orange and State of New York, have invented certain new and useful Improvements in Apparatus for Drying Bricks, of which the following is a specification, reference being had to the drawings accompanying and forming part of the same.

10 In the manufacture of brick it is necessary that the bricks be well dried before burning, and numerous methods and apparatus have been devised for such purpose. Some of the proposed devices have proved more or less successful in operation, but the most satisfactory as regards rapidity and thoroughness are extremely costly to erect and maintain. Need has long been felt for a rapid and effective apparatus which could be constructed 20 and operated at small cost, and to provide an apparatus of this character is therefore the chief object of my present invention.

In carrying out my invention in its preferred form I provide a shed of suitable size, 25 divided into a number of relatively long, narrow chambers, the walls of which extend to the ceiling of the shed and are provided at a suitable height above the floor or ground with supports for the trays or pallets on which rest the bricks to be dried. Across one 30 end of the chambers extends a passage or conduit opening into each, through which conduit flows a current of heated air, produced by heating and blowing devices provided for the purpose. The warm air, flowing along 35 the chambers under the pallets of brick, rises through the interstices between the latter, and escapes, loaded with moisture, through suitable openings in the ceiling into a common 40 collecting chamber between the ceiling and the roof. From the latter chamber the moisture-laden air escapes into the atmosphere through apertures provided for the purpose, and preferably provided with adjustable dampers or closures by which the 45 outflow of air from the collecting chamber, and consequently the flow of air through the drying chambers, can be regulated as desired for the most efficient operation.

50 The preferred embodiment thus briefly described is illustrated more fully in the annexed drawings, in which—

Figure 1 is a longitudinal vertical section of the drying shed through the center of the 55 same, also showing the truck with a loaded pallet just lifted therefrom and deposited on

the pallet ledges or supports. Fig. 2 is a transverse section on line II—II of Fig. 1, looking in the direction of the arrow. Fig. 3 is a plan view, with a portion of the ceiling 60 broken away.

Referring now to Figs. 1, 2 and 3, 1 indicates a shed of any suitable construction, provided with a ceiling 2 and roof 3, the latter being preferably of the ordinary gable form 65 shown, with the peak extending longitudinally of the shed. The side walls of the latter are constructed sufficiently tight to prevent any considerable escape of air from the interior.

Extending from floor to ceiling are longitudinal partitions 4, dividing the interior of the shed into a convenient and suitable number of long narrow chambers or tunnels 5, and provided a few feet above the floor or 70 ground with supports, as the ledges or shelves 6, on which rest the brick-pallets 7. The latter are merely rectangular frames with spaced cross-pieces, on which the bricks 8 are piled checker fashion, to permit the 75 warm dry air to flow up through the pallets and through the interstices between the bricks. The pallets are of sufficient size to rest on the opposite ledges, and are arranged 80 in succession, as indicated in Fig. 1, which shows a chamber or tunnel partly charged.

Before the tunnels at one end, and extending across the series of tunnels, is a transverse conduit 9, conveying air supplied by a blower 10, connected at one end of the same 90 and drawing its air from any suitable and convenient air-heater, merely indicated diagrammatically at 11. The top of the conduit 9 is provided with openings 12, discharging into the respective tunnels or chambers. In order to direct the incoming air 95 effectively lengthwise of the tunnels, deflectors, as 13, are provided above the discharge apertures 12, as shown. In Fig. 3 one of the deflectors is shown in plan, while the others are in horizontal section.

The tunnels being charged with the desired number of pallets, the entrance of the shed, at the right of Figs. 1 and 3, is closed in any convenient way, as by a door or doors, not shown. The blower is then started, delivering warm dry air into the conduit 9. The air, flowing along the conduit, is discharged into the tunnels, and flowing through the same passes upward through the pallets and stacks of brick. In the ceiling are long, narrow openings 14, above the respective tun-

nels or chambers. Through these openings the moisture-laden air rising from the brick stacks escapes into the space between the roof and the ceiling, constituting a common 5 collecting chamber. The bricks are thus constantly bathed in dry, heated air, and their moisture is rapidly evaporated.

In order to prevent too great a proportion of the air discharged into the tunnels from 10 escaping at once into the collecting chamber through the openings 14, the latter grow wider from the air-inlet ends of the tunnels, with the intention that the successively greater freedom of escape thus afforded will 15 cause the air to distribute itself more evenly throughout the length of the tunnel. In addition, the openings may be provided with dampers 15, by which portions or all of each 20 openings (if sufficient dampers are provided) may be closed at will and the distribution of air in the tunnels thus positively controlled. In general, a few dampers near the air-inlet ends of the tunnels will be found to answer the requirements of ordinary use.

25 Along the peak or comb of the roof extends a cupola 16, having longitudinal air-outlet openings 17 in its side walls, provided with closures or dampers 18. The latter are hinged at their bottoms and may be lowered 30 to any desired extent, thus affording convenient means for regulating the out-flow of air. The dampers are also useful to control the effect of wind, which, if the outlets were always open, might blow into the collecting 35 chamber and thus interfere with the proper draft therein. But by closing the damper on the side against which the wind is blowing, extraneous air-currents may be excluded, the other damper being opened sufficiently 40 to give the desired flow of air through the tunnels. Any convenient and suitable means for operating the dampers may be employed, as for example, the cord and pulley construction indicated at 19, in Fig. 2.

45 From the foregoing it will be seen that my invention provides means by which bricks may be rapidly and economically dried.

It will also be seen that the apparatus, can be constructed very cheaply, and that, too, 50 in the most durable manner, thus reducing the necessary amount of repairs to a minimum.

It is evident that two or more sheds or sets 55 of tunnels may be supplied with air from the same conduit, though for the sake of clearness, to keep the drawings on a larger scale, I have shown but one shed. In fact I prefer to employ at least two sets of tunnels, one of which may be drying bricks while the other 60 is in course of charging, thus making the operation of the system in a sense continuous.

It is to be understood that the construction herein described is merely the preferred 65 form of the invention, which may be embodied in various ways without departure

from its proper scope as defined by the appended claims.

What I claim is:

1. In a brick drying apparatus, in combination, a drying shed having a roof, a cupola 70 on the roof extending longitudinally of the latter and having air-outlet openings in its sides, means for regulating the flow of air through said openings, a ceiling below the roof, the space below the ceiling being divided into a plurality of drying chambers and the ceiling being provided with openings extending longitudinally of the chambers for the discharge of air from the chambers into the collecting space or chamber between the 75 ceiling and the roof, means for regulating the flow of air through the ceiling openings, an air conduit common to the chambers for supplying air thereto, as set forth.

2. In a brick drying apparatus, in combination, a long, narrow drying chamber having an air outlet opening in its top extending longitudinally thereof, means for discharging air into the chamber, and means for closing more or less of the air-outlet opening throughout the length of the chamber at will, as set forth.

3. In a brick drying apparatus, in combination, a long narrow drying chamber having an air outlet opening in its top extending longitudinally thereof, means for discharging air into the chamber, and means for regulating the flow of air through said opening, said means comprising a plurality of closures arranged longitudinally of the opening and capable of operation independent of each other, whereby more or less of said opening may be opened or closed.

4. In a brick drying apparatus, in combination, a long, narrow drying chamber having an air outlet opening in its top extending longitudinally thereof, means for discharging air into the chamber, and means for regulating the flow of air through said opening, said means comprising a plurality of hinged 105 mounted closures arranged longitudinally of the opening and capable of operation independent of each other, whereby more or less of said opening may be opened or closed.

5. In a brick drying apparatus, in combination, a long, narrow drying chamber having an outlet opening in its top extending longitudinally thereof, said opening gradually increasing in width from one end of the chamber to the other, and means for regulating the flow of air through said opening, said means comprising a plurality of closures arranged longitudinally of the opening and capable of operation independent of each other, whereby more or less of the said opening may 110 be opened or closed.

WILLIAM F. DECKER.
